UNITED STATES PATENT OFFICE.

CHRISTIAN UNRUH, OF GLEN ULLIN, NORTH DAKOTA.

LEATHER-CUTTER.

1,168,767.

Specification of Letters Patent.

Patented Jan. 18, 1916.

Application filed June 5, 1915. Serial No. 32,427.

To all whom it may concern:

Be it known that I, CHRISTIAN UNRUH, a citizen of the United States, residing at Glen Ullin, in the county of Morton, in the State 5 of North Dakota, have invented certain new and useful Improvements in Leather-Cutters, of which the following is a specification.

This invention relates to improvements in 10 leather cutters and its object is to produce a device adapted particularly for cutting leather or similar material into strips of a predetermined width.

The invention comprises a stationary roll 15 that carries a knife adapted to cut leather as the same is drawn by hand over said roll; and an adjustable guide movable longitudinally of said roll which may be set for strips of a desired width.

20 The invention consists in the combination and arrangement of parts to be hereinafter fully described in the following specification, pointed out in the appended claims and illustrated in the accompanying drawings 25 which form a part of said specification and in which—

Figure 1 is a front elevation of my improved leather cutter, with the table in section, taken on line 1—1 of Fig. 2. Fig. 2 30 is an end view of the device taken on line 2—2 of Fig. 1. Fig. 3 is a vertical sectional view through the roll and guide and is taken on line 3—3 of Fig. 1. Fig. 4 is an end view taken on line 4—4 of Fig. 1, with the roll 35 and knife turned half way around. Fig. 5 is a front view of an auxiliary roll section which may be connected to the main roll when a piece of leather of exceptional width is under operation. Fig. 6 is a cross section 40 on line 6—6 of Fig. 5. Fig. 7 is a front elevation of the roll and knife in the position shown in Fig. 4 and with an auxiliary guide secured to the shaft. Fig. 8 is a cross section taken on line 8—8 of Fig. 7. Fig. 9 is a 45 front view of a modification of a portion of the guide. Fig. 10 is a plan view of Fig. 9.

Like reference characters indicate corresponding parts throughout the several views.

My leather cutter comprises the base 1 50 which may be bolted as at 2 to a suitable table or support 3 and to said base 1 the standards 4, 4 are bolted that carry the shaft 5 on which the sectional roll 6, 6 is carried and between and to the sections of said roll 55 the knife 7 is secured, said knife being

formed with the diagonally opposite relatively reversed cutting edges 8, 9. To the knife 7 adjacent to one cutting edge 8 a slotted gage 10 is secured as at 11, the opposite end of said gage being carried by a 60 bracket 12 secured to the shaft 5 between a pair of nuts 13, 13. Upon said gage 10 an adjustable guide 14 is arranged and the same is provided with a transversely extending finger 15 held in position by a pin 15^a and 65 said finger is formed with a lug 16 against which one edge of the leather strip, being cut, rides. The guide 14 is set upon the gage 10 a distance from the knife equal to the width of strip to be cut; the leather piece 70 is then manually drawn over the roll against the knife, one edge of the leather riding against the lug 16 and the entire piece of leather extending from said lug laterally beyond the knife. The operator stands back 75 of the roll or in a position with the roll between himself and the table and pulls the leather over the roll against the knife. The operation just described is the one employed 80 to cut the leather into strips of ordinary sizes.

To cut the leather into exceptionally large strips the roll 6, 6 is turned half way around or into the position illustrated in Figs. 4 and 85 7 thus moving the knife edge 9 into operative position and disposing the gage 10 and guide 14 in inoperative position or back of the cutting edge. A bracket 17 is placed between the nuts 13, 13 upon the shaft 5 to support the adjustable gage 18 provided 90 with the sliding guide 19. The guide 19 is similar in every way to the guide 14 and is provided with a finger 20 similar to finger 15. To cut a strip of leather from a leather sheet the guide is set upon the gage a distance from the knife edge equal to the width of the strip to be cut and the operation performed in a manner similar to that previously described. Since the gage 18 is not 95 connected to the knife it can be adjusted about the shaft independently of the knife. To suit leather of various thicknesses I provide an adjustable finger comprising hinged sections 21, 21 and said sections are formed with lugs 22 in which the ends of a spring 105 23 are secured which spring tends to draw the free ends of the sections 21 together. A lug 24 depends from one section 21 and against said lug one edge of the sheet of leather rides, this edge being inserted be- 110

tween the free ends of said sections. The opening 25 in the one section 21 is to receive the pin by which it is secured to the guide 14. When wide strips of leather are to be cut from a large sheet of leather it may be necessary to lengthen the roll in order to support the sheet. The roll 6, 6 is formed with terminal sockets 26 and the shaft 5 with a socket 27 which sockets are adapted 10 to receive rods 28 of an auxiliary roll 30, which is carried upon an auxiliary shaft 31 journaled in standards 32 which may be secured to the table. Pin 29 carried by one standard 4 enters shaft 5 to normally prevent rotation of the roll 6—6.

What is claimed is:—

1. In a leather cutter, a sectional roll, a knife carried thereby, a shaft journaled in suitable bearings and supporting said roll, 20 a gage carried by said knife and shaft and extending longitudinally of said roll, a guide slidably carried by said gage and a leather-engaging finger carried by said guide.
2. In a leather cutter, a sectional roll, a knife carried thereby, a shaft journaled in suitable bearings and supporting said roll, a gage carried by said knife and shaft and 30 extending longitudinally of said roll, a guide slidably carried by said gage and a

sectional adjustable leather-engaging finger carried by said guide.

3. In a leather cutter, a sectional roll, a two-edged reversible knife carried by said roll, a shaft supporting said roll and projected therebeyond, a gage adjustably carried by said shaft, a guide movable longitudinally of said gage and an adjustable leather-engaging finger carried by said guide. 35

4. In a leather cutter, a sectional roll, a two-edged knife carried by said roll, a shaft supporting said roll and projected therebeyond and formed with a socket in one end, an auxiliary roll, rods terminally carried 40 thereby for insertion in the sockets of the sectional roll and shaft, a shaft supporting said auxiliary roll, a gage adjustably carried by the first named shaft, a guide movable longitudinally of said gage and an adjustable finger carried by said guide. 45

In testimony that I claim the foregoing as my own I have hereto affixed my signature in the presence of two subscribing witnesses.

CHRISTIAN UNRUH.
